UNITED STATES PATENT OFFICE.

DORAH W. WILT, OF SAN DIEGO, CALIFORNIA.

ELECTRIC-CIRCUIT LOCK.

1,059,583.

Specification of Letters Patent. Patented Apr. 22, 1913.

Application filed August 26, 1911. Serial No. 646,275.

To all whom it may concern:

Be it known that I, DORAH W. WILT, a citizen of the United States, residing at San Diego, in the State of California, have 5 invented new and useful Improvements in Electric-Circuit Locks, of which the following is a specification.

The general object of the invention is to lock in open position, the closer or 10 controller of an electric circuit for delivering current either to an electric motor or to the ignition apparatus of an internal combustion engine, and to this end the invention is adapted for use chiefly, with motors for 15 operating propelling devices of conveyances such as motor vehicles, airships, boats and the like.

Other objects will appear and be better understood from the following description 20 taken in connection with the accompanying drawings, in which,

Figure 1 is a front elevation of one embodiment of the invention. Fig. 2 is a view 25 similar to Fig. 1 but with the door or closer in open position. Fig. 3 is a detail of the lock mechanism showing the position of the parts when the door is locked. Fig. 4 is a detail side elevation of the door with the flange thereof and part of the lock-bolt 30 broken away.

In the embodiment shown in the drawings the device is used in connection with what is known as a coil box which contains the spark coils forming part of the ignition 35 circuit for an internal combustion engine. At the outset it may be stated that this construction is shown merely to illustrate one application of the invention and, therefore, I do not intend to limit myself to such use 40 for the reason that the device is not dependent upon any particular form of ignition circuit and might be used equally as well with an ignition circuit from which spark coils are eliminated, such as where 45 magnetos generate the current and moreover I do not intend that I shall be limited to use my device only with an ignition circuit, since the same may also be employed with the circuit of an electric motor, such 50 as is found in various types of self-propelled vehicles.

5 indicates the body of the box or casing which on account of its association with the usual controlling switch 6, will subsequently be termed the "switch box." This term is 55 generic and intended to apply to the ordinary coil box or a box similar to that shown, but minus the coils. 7 indicates the closure for the box which may be a door or cover and may be detachably connected to the box 60 or hinged thereto as indicated at 8. 9, 9 indicate the conducting wires of an electric circuit in which is included the switch 6, coil 10 and the contacts 11, 11. These parts are all contained in the casing and supported 65 therein, in any preferred manner, preference being given to construction wherein the contacts or sockets 11 are supported by the door 7.

a indicates generally a permutation lock, 70 the knob or handle of which is designated by 12 and arranged exteriorly of the door 7. The dial is indicated by 13 and the tumblers by 14, the latter, as usual, being arranged 75 interiorly of the casing when the door is closed.

15 indicates the bolt of a latch which has end projections 16 extending through the inturned flange 17 of the door and adapted to move over the inner side of a keeper 18, 80 herein shown as a strip extending inwardly from a side of the box.

19 indicates a handle extending through a slot 20 in the door and connected with the bolt 15 so as to slide the latter, whereby, to 85 disengage the portion 16 from the keeper 18.

b indicates a device adapted, when in one position, to obstruct the bolt 15. In the present instance this device, in addition to providing an obstruction for the bolt, is 90 further adapted to act as a controller or closer for the electric circuit and is constructed so as to be received by the contacts 11 when the door is unlocked.

19' indicates a pivot for connecting the 95 element b to the door 7 and 20' a handle at the outer end of the pivot which serves as a means for turning the element b. The element b is preferably of non-conducting material but the end portion 21 thereof is 100 preferably covered with conducting material such as metal, so as to complete the cir-

cuit when in engagement with the contacts 11. The end or side portion 22 of the element *b* is disposed angularly to the portion 21 and has a cam finger 23 adapted to be received by the notches 24 of the disks 14 when the said notches are all in alinement as shown in Fig. 2.

25 indicates a projection on the element *b* adapted to abut the bolt 15 when the door 10 is locked, as shown in Fig. 3.

26 indicates a spring for projecting the extension 16 through the flange 17.

27 and 28 indicate stops for limiting the inward movement of the bolt, one of which 15 also limits the turning movement of the element *b*.

Suitable fastening means such as screws 29, pass through the bottom or inner wall of the box and serve to connect the same to 20 any convenient portion of the vehicle or other device to which the box is applied.

30 indicates screws which pass through the door 7 and screw into any convenient part in the interior of the casing so as to 25 prevent the door from being easily opened when the said door is unlocked.

If the door be in open position and the notches in the disks in alinement and the cam finger 23 in the notches, the portion 21 30 of the element *b* or circuit closer will be in engagement with the contacts 11, 11 and thus the circuit will be complete. Now if the door be swung to closed position, the projections 16, 16 will move behind the 35 keeper 18, whereby, the door will be latched but not to prevent its being opened again if the bolt be slid by moving the handle 19 in the required direction. It will also be observed that the circuit is still closed when 40 the door is so latched. This will be the normal positions of the parts when the motor is operating and the screws 30, which now secure the door to the casing will prevent the said door from being opened easily.

45 Now, if the motor be stopped, the current may be turned off by turning the switch 6 in the required direction. This, however, does not prevent the completion of the circuit when the switch is again turned on.

50 Now in order to prevent the switch 6 from completing the circuit if turned on as last stated, the knob 12 of the lock *a* is turned so as to move the disks clockwise as viewed in Fig. 2. This will have the effect of camming the element *b* to the position shown 55 in Fig. 3, whereby, the side portion 21 will move from engagement with the contacts 11 and at the same time the projection 25 will move into the path of the projection 32

60 of the bolt 15. In this position, it will be seen that the end of the cam finger now bears on the periphery of the tumblers or disks 14 and in as much as the notches in the latter are now out of alinement it will

be necessary to know how to manipulate the 65 knob 12 so as to bring the notches 24 again into alinement and this combination, of course, will be only known to the operator, or some authorized person. Thus, it will be seen that when the door is locked in 70 closed position against opening movement, the circuit will be broken, and when unlocked and capable of latching, the circuit will be closed. When the tumblers are arranged so that the slots therein aline, the 75 element *b* is actuated to dispose the finger 23 within the alining slots or notches and the arm 21 thereof engages the contacts 11 to effect the closing of the circuit. By so arranging the parts as to enable the circuit 80 to be closed only when the door is unlocked, admits of readily inspecting the contacts when poor ignition is observed, without the trouble of manipulating the lock to permit the withdrawal of the latch. 85

Although I have shown and described one embodiment of my invention it is to be understood that I am not to be limited to the specific arrangement and construction of parts since various changes will be made, 90 within the scope of the appended claims without departing from the spirit or sacrificing any of the advantages of the invention.

What I claim as new is:

1. The combination with a switch box and 95 a removable closure therefor, of a circuit extending through the box, a latch for said closure, a rocking element disposed within said box and comprising relatively angular arms, said element being also provided with 100 a projection adapted to lie in the path of movement of said latch, one of said arms being adapted to break the circuit, and rotatable means associated with the other arm for maintaining the first mentioned arm in 105 a position to close the circuit.

2. The combination with a switch box and 110 a removable closure therefor, of a circuit extending through the box, a latch for said closure, a rocking element disposed within said box and comprising relatively angular arms, said element being also provided with a projection adapted to lie in the path of movement of said latch, one of said arms being adapted to break the circuit, rotatable 115 means associated with the other arm for maintaining the first mentioned arm in a position to close the circuit, and means for limiting the movement of said rocking element. 120

3. The combination with a switch box and 125 a removable closure therefor, of a circuit extending through said box, a latch for said closure, and extending longitudinally of said casing, means for normally retaining the latch in latching position, a rocking element disposed within the box and comprising relatively angular arms provided with a

projection adapted to lie in the path of movement of said latch, one of the arms of said element being adapted to break the circuit, and rotatable means associated with the 5 other arm for maintaining the first mentioned arm in a position to close the circuit.

In testimony whereof I affix my signature in presence of two witnesses.

DORAH W. WILT.
